UNITED STATES PATENT OFFICE.

CHARLES DABELSTEIN, OF DETROIT, MICHIGAN.

SHOVEL ATTACHMENT.

1,179,809.

Specification of Letters Patent. Patented Apr. 18, 1916.

Application filed January 11, 1915. Serial No. 1,493.

To all whom it may concern:

Be it known that I, CHARLES DABELSTEIN, a citizen of the United States of America, residing at Detroit, in the county of Wayne and State of Michigan, have invented certain new and useful Improvements in Shovel Attachments, of which the following is a specification, reference being had therein to the accompanying drawings.

10 This invention relates to a shovel attachment by which snow and ice can be expeditiously removed from streets, sidewalks and other surfaces.

The primary object of my invention is to 15 provide a shovel attachment of the above type wherein novel means is employed for subjecting snow and ice to a blow flame or hot blast that will quickly melt snow and loosen ice, whereby the ice can be scooped 20 up by the shovel or otherwise removed.

A further object of this invention is to 25 provide a shovel attachment of the above type wherein a liquid fuel, as kerosene or gasoline can be utilized for heating the lower end of the shovel and for melting ice. Novel means is also employed for producing 30 a blast of air contiguous to a flame whereby the flame will have sufficient intensity as to expeditiously soften or loosen indurate frozen matter.

The above and other objects are attained 35 by a simple, durable and inexpensive mechanical construction which will be hereinafter specifically described and then claimed.

Reference will now be had to the drawing, wherein—

Figure 1 is a longitudinal sectional view 40 of a portion of a shovel attachment in accordance with my invention; Fig. 2 is a plan of the same partly broken away and partly in section, and Fig. 3 is an enlarged longitudinal sectional view of a portion of the shovel, illustrating a modification of 45 my invention.

In the drawing, the reference numeral 1 denotes a shovel or scoop having a handle rod 2. Riveted or otherwise connected to the bottom of the scoop 1 is a metallic casing 3 which has the outer end thereof open in proximity to the outer edge of the shovel or scoop. In the casing 3, contiguous to the bottom thereof, is a horizontal partition 4 and a vertical partition 5, said partitions 50 coöperating with the side and end walls of the casing 3 in providing a liquid fuel reser-

voir 6. The reservoir 6 is adapted to contain gasoline or kerosene and is filled through the medium of a filler opening 7 normally closed by a cap 8, said filler opening being adjacent one side of the casing 3, as best shown in Fig. 2.

The vertical partition 5, is provided with wick guides 9 and extending through said guides into the reservoir are flat wicks 10. The outer ends of the wicks 10 extend through the open end of the casing 3 and are held against the bottom of the shovel or scoop 1 by a transverse wick adjusting rod 12, which has one end thereof provided with a knurled button 13. This wick adjusting rod is of a conventional form, as commonly employed for moving a plurality of wicks, for instance, as in a small oil stove, and permits of the flat wicks being adjusted 70 from time to time, and provision is made for supplying a blast of air to the outer ends of the wicks, to increase the intensity of flames when the wicks are ignited. This is accomplished by an auxiliary casing 14 75 connected to the bottom of the shovel or scoop 1 and the end of the casing 3.

The auxiliary casing 14 has the wall thereof provided with an air inlet opening 15 and within said auxiliary casing is a 80 horizontally disposed fan 16. The shaft 17 of said fan extends through the bottom of said casing and is provided with a crank 18 connected by a flat rod 19 to a slide 20. The slide 20 is movable in guides 21 carried by 85 the bottom of the casing 3 and said slide is connected by a pitman 22 to the crank 23 of a roller shaft 24. The roller shaft 24 is journaled in depending bearings 25 carried by the bottom of the casing 3 and 90 mounted upon said shaft is a roller 26. The bottom of the casing 3 is offset to provide clearance for said roller, which is preferably located in the longitudinal axis of the shovel or scoop.

The horizontal partition 4 coöperates with the bottom of the casing 3 in providing a horizontal air channel or flue 27 in communication with the auxiliary casing 14, and when the shovel or scoop is moved over a surface with the roller 26 in engagement with the surface, the fan 16 is revolved to force air through the channel or flue 27, whereby there will be a blast at the outer ends of the wicks 10.

In Fig. 3 of the drawing, there is illustrated a slight modification of the invention,

wherein the auxiliary casing 14, the revoluble fan 16 and the air channel or flue 27 are dispensed with, retaining the body 7, reservoir 6, partition 5, wick guides 9, and wick 10 adjusting means 12. A roller 26^a is utilized in connection with a shaft 24^a, a crank 23^a, and a connecting rod 28 for operating a piston 29 in a pump cylinder 30, carried by the bottom of a casing 3^a contiguous to the roller 26^a. As a matter of good construction the pump cylinder 30 forms part of the bottom of the casing 3^a and the roller 26^a extends into the casing, thus permitting of the outer end of the shovel or scoop being easily placed in engagement with a surface. The cylinder is provided with an air inlet port 31 having a conventional form of check valve 32 and said cylinder is connected by a pipe 33 to a transverse header 34 within the casing 3^a. The header 34 has a branch pipe or tube 35 extending out of the casing 3^a in proximity to the outer end of a wick 10^a and when the shovel or scoop is moved over a surface, the pump is operated 25 to supply air to the outer end of the wick and produce a blast that will facilitate the removal of frozen matter.

By detachably connecting the casing 3, as well as the auxiliary casing 14, to the bottom of the shovel or scoop 1, such shovel or scoop can be used for other purposes than that herein shown, and with the casing made of light and durable sheet metal very little

weight is added to the shovel or scoop and consequently it can be easily handled and manipulated for thawing ice.

While in the drawings there are illustrated the preferred embodiments of my invention, it is to be understood that the structural elements are susceptible to such changes, in the size, shape and manner of assemblage, as fall within the scope of the appended claim.

What I claim is:—

The combination with a shovel, of a casing carried thereby and having the outer end thereof open, a fuel reservoir in said casing, an air channel between said reservoir and the bottom of said casing, a plurality of wicks extending from said fuel reservoir to the outer open end of said casing and adapted to maintain flames beneath said shovel, a revoluble roller supported by said casing, a slide supported by the bottom of said casing actuated by a rotary movement of said roller, a fan at the rear of said fuel reservoir and at the inner end of said air channel adapted to be revolved by reciprocatory movement of said slide, and means adapted for adjusting said wicks.

In testimony whereof I affix my signature in presence of two witnesses.

CHARLES DABELSTEIN.
